Primary Examiner — Holly Baynham(57) **CLAIM**

The ornamental design for a wallet for cards, cash and memory, as shown.

DESCRIPTION

FIG. 1 is a front view of a wallet for cards, cash and memory showing my new design, the bottom left compartment for electronic memory and opening for handling cash.

FIG. 2 is a rear elevation view thereof, the bottom left and right compartment for electronic memory.

FIG. 3 is an enlarged right side view thereof.

FIG. 4 is an enlarged left side view thereof.

FIG. 5 is an enlarged bottom view thereof.

FIG. 6 is an enlarged top view thereof, showing an opening compartment for storage.

FIG. 7 is the right rear perspective view thereof, showing open compartments for storage such as cash, cards and electronic memory.

FIG. 8 is the left rear perspective view thereof, showing open compartments for storage such as cash, cards and electronic memory.

FIG. 9 is the right front perspective view thereof, showing open compartments for storage such as cash, cards and electronic memory.

FIG. 10 is the left front perspective view thereof, showing open compartments for storage such as cash, cards and electronic memory.

FIG. 11 is the front left perspective upright view thereof, showing open compartments for storage such as cards, and electronic memory.

FIG. 12 is the front right perspective upright view thereof, showing open compartments for storage such as cards, and electronic memory.

FIG. 13 is the rear left perspective upright view thereof, showing open compartments for storage such as cards, cash and electronic memory; and,

FIG. 14 is the rear right perspective upright view thereof, showing open compartments for storage such as cards, cash and electronic memory.
